UNITED STATES PATENT OFFICE.

SIEGFRIED ROSENZWEIG, OF NEW YORK, N. Y.

VALVE-GEAR FOR STEAM-ENGINES.

1,384,855.

Specification of Letters Patent. Patented July 19, 1921.

Application filed December 8, 1920. Serial No. 429,114.

To all whom it may concern:

Be it known that I, SIEGFRIED ROSENZWEIG, a citizen of the United States, and a resident of the city of New York, in the county and State of New York, have invented certain new and useful Improvements in Valve-Gears for Steam-Engines, of which the following is a specification.

My invention relates to a valve arrangement for reciprocating steam engines of the puppet valve type, and consists of certain improvements therein which will first be described in connection with the accompanying drawings and will then be more particularly pointed out in the claims.

In said drawings:

Figure 1 represents in longitudinal vertical section a valve chamber and parts contained therein embodying my improvements in their preferred form together with a portion of the steam or engine cylinder with which the valve chamber is associated.

Figs. 2 and 3 are detached views, on enlarged scale, of the elbow levers for operating the valve spindles.

Fig. 2 represents in plan and in side elevation the elbow lever for operating the steam valve spindle, and

Fig. 3 represents in similar views the elbow lever for operating the exhaust spindle.

The valve gear embodying the improvements shown herein is of the same general type as that illustrated in my companion application, Serial No. 427,290, filed November 30, 1920, comprising, as it does, steam and exhaust valves mounted and arranged one upon the axial prolongation of the other, provided with spindles, one for each valve, the one spindle passing axially through and telescoping with the other, the telescoped ends of the spindles extending between lift members (one for each spindle) mounted in suitable bearings at their exterior opposite free ends engaging each its appropriate one of the telescoped spindle ends, and an operating shaft provided with suitable cam lifts or tappets for actuating the lift members.

In the embodiment of the invention illustrated in my companion application, Serial No. 427,290, the two sets of valves are placed parallel with one another crosswise of and at the opposite ends of the engine cylinder.

In the embodiment of the same shown herein the two sets of valves are placed in tandem fashion lengthwise of the engine cylinder.

The improvements subject of my present application are measurably the outgrowth of the above-noted primary difference between the two embodiments.

60

Referring now to the accompanying drawing, A is a representation, largely diagrammatic, of that portion of the engine cylinder upon which the valve chambers are mounted. The two valve chambers may be mounted on 65 and secured in any suitable way to the engine cylinder, extending lengthwise of the latter, one upon the axial prolongation of the other and parallel with the axis of the engine cylinder, with an intermediate space 70 between their interior opposite ends for the passage of the valve operating cam or tappet shaft. I prefer to form them, as shown, of a single unitary structure cast in one with the engine cylinder, divided internally by 75 suitable diaphragms or partitions into three compartments—two end chambers or compartments to receive the two sets of intake and exhaust puppet valves which serve the opposite ends of the engine cylinder, and an 80 intermediate compartment to receive the cam or tappet portion of the valve operating shaft which extends crosswise of said intermediate compartment through suitable supporting bearings (not shown) formed on 85 opposite sides of the same. The two end valve compartments or chambers are designated B, the intermediate compartment or chamber, B⁴, and the cam or tappet valve-operating shaft, E. This shaft may be of 90 any suitable type, whether axially oscillatory or longitudinally reciprocatory. For the purpose of my present improvements, I prefer a tappet shaft of the axial oscillatory type, and it is so represented in the 95 drawings. It is provided, as shown, with a boss e² provided with two sets of valve-operating devices, consisting each of two end lifts e' and an intermediate recess e, formed diametrically opposite to one another upon 100 the periphery of the boss. The opposite ends of the valve chamber are provided with removable covers B', and the intermediate compartment B⁴ is provided with a removable cover B⁵.

105

The valve cages, valves, valve fittings and valve gear are the same for each compartment B, so that a description of one will answer for both.

The valve chamber is formed with a port a 110 through which steam is admitted to and exhausted from that end of the engine cylin-

der with which the valve chamber is associated, and is machined out internally to provide a seat for a sectional valve cage C C' which is removably but closely fitted 5 therein and abuts at its inner end against an annular shoulder b , the joint between the two being made steam tight by suitable means (not shown) to prevent the escape of steam into the intermediate tappet compartment B⁴. The cage is also provided with a steam and exhaust port which registers with the port a in the valve chamber. The two sections, C, C', of the valve cage contain, the former the intake valve V and 10 its valve seats v , and the latter the exhaust valve V' and its valve seats v' —the section C' being seated against the annular shoulder b , and the section C butting up against section C', the abutting ends of the two sections 15 being suitably fastened together, or not, as preferred. The cage is held in place against the shoulder b by a clamping ring B² attached to the inner face of the cover B' by legs B³.

20 The two seats v of the intake valve V are in section C, the one upon an annular ledge c' and the other upon a diaphragm or partition D; the two seats v' of the exhaust valve V' are correspondingly located in section C' upon an annular ledge c^2 , and a diaphragm D', respectively. The valve chamber is provided with a suitable steam intake passage S and an exhaust passage X.

25 The two sets of valves are arranged, tandem fashion, in axial alinement, one on the prolongation of the other; and the pair of valves for each set are correspondingly arranged relatively to each other, with telescoping spindles, the spindle of one of the 30 valves—in this instance the steam valve V—passing longitudinally and axially through the spindle of the other valve, and the two, which snugly telescope together, being capable of independent longitudinal movement.

35 The exhaust valve V' is located in the valve cage between the diaphragms D and D'. Its central tubular core fits upon, and is guided in its movements by, an axial tubular guide x' fast on the diaphragm D', and preferably cast in one therewith. The exhaust valve spindle w' (which is made tubular for purposes hereinafter indicated) 40 passes axially through the diaphragm D' and tubular guide x' , until it brings up against the closed end of the central tubular core of the exhaust valve—the tubular guide x' serving to support and guide the exhaust valve V', and also the exhaust valve 45 spindle w' which fits snugly within it. The valve is held normally in closed position, against the lifting action of its spindle, by yielding pressure exerted by a spring s' interposed between the head of the valve and 50 the diaphragm D. Similarly, the intake

valve V is held in closed position with yielding pressure by a spring s interposed between the head of the valve and the valve chamber cover B', and its tubular central core fits upon the exterior of a tubular guide x on diaphragm D in exact axial alinement with the exhaust valve tubular guide x' in the diaphragm D'. The steam valve spindle w extends into and through the tubular exhaust valve spindle w' which it closely fits, 55 thence out through a suitable aperture in the head of the exhaust valve V' and thence through the diaphragm D and tubular guide x thereon (which it closely fits) until its outer end brings up against the closed head 60 of the central core of the intake valve V. The steam valve spindle w may be a continuous one-piece stem from end to end, but, at a point y in its length between the two diaphragms D, D', it is preferably divided 65 crosswise into two sections with close fitting meeting ends, in order to allow for slight variations in axial alinement between the two valves that may occur during their operation.

90 The cam shaft E extends diametrically across between the two valve compartments in a position to conveniently operate the valve spindles through the intermediary of lift members supported in bearings, between 95 the telescoped ends of the valve spindles and the tappet shaft, in position to engage the ends of their respective valve spindles, and to be actuated by said shaft to move their respective spindles in a direction to open the 100 valves appropriate to those spindles against the stress of their closing springs. The telescoped ends of the two spindles of each of the two sets of valves extend through the diaphragms D' of their respective cages into 105 the space intervening between the said diaphragms and the cam or tappet shaft, and on diametrically opposite sides of said shaft. The lift members for each pair of valve spindles w , w' consist, in the present 110 instance, of two levers L, M, preferably of the elbow type, pivoted in bearings N attached to the valve cage, and preferably to the diaphragm D' of the section C' of the cage, on that side of the diaphragm facing 115 the cam shaft E, as shown, and designed and arranged to engage and actuate the valve spindles. To this end, the two levers face one another, and are provided with rollers O at their elbows which are received in the 120 cam recess e formed for their reception in the periphery of the boss e^2 of the cam shaft E, said recess terminating at the ends in lifts e' , the one to actuate the lever L which operates the intake valve V, the other to 125 operate the lever M which operates the exhaust valve V', the rollers O at the elbows of the levers serving to reduce the friction between the elbows of the levers and the cam lifts over which they pass. The 130

preferred construction of these levers is represented in Figs. 2 and 3. The tip *l* of the free end of the lever *L* extends far enough toward the telescoped spindle ends to come 5 opposite to and rest against the base of the steam valve spindle *w*. The free end of the other lever *M* is forked as shown more clearly in Fig. 3, the prongs *m* of the fork straddling the tip *l* of the lever *L* and ex- 10 tending far enough inward to reach and bear against a laterally projecting flange *w*² on the annular base of the tubular exhaust valve spindle *w*'. A clearance slot *w*³ in the end of the exhaust spindle permits the play 15 of the elbow lever *L* necessary to give the proper lift to the steam valve spindle *w*. The levers *L*, *M*, during the valve-lifting operation, are held in close contact with their respective valve spindles and cam lifts by the 20 yielding pressure exerted by the steam and exhaust valve-closing springs *s*, *s*'.

The face-to-face arrangement of the two levers permits the cam lifts for the two valves of each set to be placed at opposite 25 ends of one and the same recess as shown, provided the length of the latter be such that, at the maximum stroke of the oscillatory tappet shaft, the cam lift at one end of the recess will not reach the elbow of the 30 lever which is designed to be operated by the cam lift at the other end of the recess. It will, of course, be understood that the two sets of lifting members *L*, *M*, and their operating cam lifts or tappets are so disposed 35 relatively to one another that when the lift member *L* of one set is operated to open the intake valve of the pair which serve one end of the engine cylinder, the lift member *M* of the other set simultaneously is operated to 40 open the exhaust valve of the pair which serve the opposite end of the engine cylinder.

The marginal portion of the diaphragm *D* surrounding the annular valve seat *v* 45 thereon preferably has openings *d* in it (as shown) to facilitate the delivery of steam to the steam admission cylinder port *a* when the intake valve *V* is opened.

The mode of operation of my improved 50 valve gear will be manifest from the description already given, and requires no further explanation.

Having described my improvement and the best way now known to me of carrying 55 the same into practical effect, I state in conclusion that I do not limit myself to the structural details hereinbefore shown and set forth in illustration of my invention, since manifestly the same can be varied with- 60 out departure from the spirit of the invention; but what I claim herein as new and of

my own invention, and desire to secure by Letters Patent is as follows:—

1. In a valve gear for steam engines the combination of the following elements, 65 namely—an engine cylinder; two valve chambers mounted, at an interval from one another, on and lengthwise of said cylinder, one on the axial prolongation of the other; two sets of steam and exhaust valves, one 70 for each valve chamber, mounted and arranged in their respective chambers—one set upon the axial prolongation of the other; valve spindles, one for each valve, the spindles of the two valves of each set passing 75 the one axially through, and telescoping with the other, the telescoped ends of the two sets of spindles projecting in axial alignment with one another through the interior opposite closed ends of their respective 80 chambers into the intervening space which separates said chambers; lift members, one for each spindle, mounted and movable in bearings on the interior opposite ends of their respective valve chambers on opposite 85 sides of the telescoped ends of the sets of valve spindles with which they are respectively associated with their free ends engaging the one the outer and the other the inner one of said telescoped ends; and a cam 90 or tappet valve-operating shaft extending through the interval which separates the two valve chambers crosswise of and between the opposed telescoped ends of the two sets of valve spindles, and lift members 95 with which they are associated and provided with two sets of recesses and cam lifts located on diametrically opposite faces of said shaft to engage and actuate the lift members of two sets—the combination being and act- 100 ing substantially as set forth.

2. The combination of elements of claim 1, when the lift members are composed of elbow levers pivoted at their exterior opposite ends in their supporting bearings facing 105 one another with their interior opposite free ends in engagement with their respective telescoped spindle ends, and their elbows in engagement with the cam shaft.

3. The combination of elements of claim 110 1, when the two valve compartments or chambers consist of a unitary cylindrical casing extending lengthwise of the engine cylinder and provided with removable covers at its ends and two valve cages contained 115 therein separated at their interior opposite closed ends by an interval which provides an intermediate compartment for the housing of the valve gear and the tappet portion of the operating shaft.

In testimony whereof I affix my signature.
SIEGFRIED ROSENZWEIG.
